UNITED STATES PATENT OFFICE.

LEE J. CHAPMAN, OF COLUMBUS, OHIO, ASSIGNOR OF ONE-HALF TO
DENMAN KINSELL, JR., OF SAME PLACE.

ELECTROMASSAGE DEVICE.

SPECIFICATION forming part of Letters Patent No. 683,680, dated October 1, 1901.

Application filed July 31, 1901. Serial No. 70,381. (No model.)

To all whom it may concern.

Be it known that I, LEE J. CHAPMAN, a citizen of the United States, residing at Columbus, in the county of Franklin and State of Ohio, have invented a new and useful Electromassage Device, of which the following is a specification.

This invention relates to a novel electromassage device designed to facilitate the making of electrotherapeutic applications to the human body.

In faradic medical appliances of ordinary type it is usual to employ conductive cords from the induction-coil to the electrodes in contact with the body and other cords from the battery-cell to the coil. These connections are apt to break and shock the patient, and they prevent the electrodes from being passed continuously around the body or around a limb, because of the wrapping of the conducting-cords around the treated member and the necessity for removing the electrodes from contact with the patient until the conducting-cords are unwound.

An important object of the present invention, therefore, is to produce a faradic electromassage implement combining in compact form for manipulation by one hand the electrodes, coils, battery, electrical connections, and current-regulating mechanism without the employment of conducting-cords or other appurtenances which would tend in any manner to interfere with the continuous manipulation of the instrument for the purpose of massaging the patient and simultaneously subjecting the tissues to faradization.

A further object of the invention is to provide the instrument with electrodes arranged to encompass the greatest possible amount of tissue within the electrical field and so arranged that in manipulating the device to massage the patient the tissues will be subjected alternately to the anode and cathode as the device is moved backward and forward in the usual manner.

Another object of the invention is to so form the applying-plates or electrodes that they will be well adapted for massaging purposes, as well as for making the necessary electrical contact with the body, and will serve to protect and conceal the electrical

connections mounted on the under side of the base.

A still further object of the invention is to utilize the battery-cell as a handle or grip detachably secured at the side of the base opposite the applying-plates or electrodes and retained in place by movable arms, which serve as electrical conductors, opening and closing devices for the primary circuit, and retaining means for securely holding the battery-cell in position.

Other objects of the invention are to provide for the regulation of the strength of the current without breaking the contact between the electrodes and the body and to subject the patient to the action of either a faradic or induced current or a direct battery-current, as desired, without interrupting the treatment.

To the accomplishment of the several objects stated and others subordinate thereto, all as will hereinafter more fully appear, the invention in its preferred embodiment consists in the construction and arrangement of parts to be hereinafter fully described, illustrated in the accompanying drawings, and embraced within the scope of the appended claims.

In said drawings, Figure 1 is a perspective view of my electromassage instrument complete and illustrating in dotted lines the manner in which the retaining-arms are swung back to permit the detachment of the battery-cell when necessary. Fig. 2 is a central longitudinal sectional view of the subject-matter of Fig. 1, but showing the battery-cell in elevation. Fig. 3 is a bottom plan view showing the form and relation of the electrodes or applying-plates. Fig. 4 is a view similar to Fig. 3 with the electrode-plates removed and showing the arrangement of the wiring, which is housed and protected by the plates. Fig. 5 is a side elevation of a portion of the instrument looking toward the side thereof opposite to that shown in Fig. 1, and Fig. 6 is a diagrammatical view illustrating the electrical arrangement of the device.

Like characters are employed to designate corresponding parts throughout the views.

1 indicates what may be termed the "base,"

which is preferably, though not necessarily, of elliptical form, at the opposite sides of which are located the handle 2 and the applying or electrode plates 3 and 4, the handle being disposed longitudinally of the base and the plates 3 and 4 being located at the opposite sides of the transverse insulating-strip 5, which serves to insulate the plates from each other. The electrode-plates are 10 dished or of concavo-convex form in order to impart a smooth rounded exterior surface thereto for the purpose of facilitating their use as massaging and applying surfaces and to provide an interior space between the 15 plates and the base for the interposition of the wiring and other electrical connections, to be hereinafter described.

The handle 2 is formed by the cylindrical cell 6 of the battery, removably retained by 20 securing-bands 7 and 8, passed around the cell and screwed or otherwise secured to the base 1, as indicated at 9 in Fig. 1. The cell or handle is spaced from the base a sufficient distance to permit the interposition of the induction-coil 10, the head-blocks 11 and 12 of which are set into the base 1 and constitute supports for the combined handle and battery. The induction-coil comprises, as usual, a soft-iron core 13, a primary coil 14, and a 25 secondary coil 15 and has associated with it the usual rheotome or interrupter, comprising a plate 16, (secured to the block 12 and extended thereabove to form a stop opposed to the rear end of the battery or handle,) a 30 vibratory spring 17, carrying the armature 18, a contact-screw 19, and a binding-post 20, which latter is mounted upon the base 1 in rear of the induction-coil.

In carrying out the invention the handle 40 may be retained in place by any suitable means; but inasmuch as the handle also constitutes the battery I prefer to provide a pair of angular arms 21 and 22, pivotally mounted upon the base, as by screws 23 23^a, adjacent to its front end and designed to be 45 swung into engagement with the binding-screws 24 and 25, extending beyond the front end of the cell and in electrical connection with positive and negative elements—as, for 50 instance, the carbon and zinc plates of the battery.

The upper ends of the arms 22 are provided with recesses 26, which receive the binding-screws to prevent the accidental disconnection of the arms, which by this arrangement 55 are made to constitute retaining means for the handle or battery, electrical conductors extending between the poles of the battery and the wiring mounted under the base, and 60 opening and closing devices for the primary circuit, since it will be seen that by swinging either of these arms out of contact with its binding-post the battery-circuit will be opened and that by swinging both arms back 65 to the positions indicated in dotted lines in Fig. 1 the cell is released and may be with-

drawn from its bands and another inserted in lieu thereof, as occasion may require.

Upon the base, at one side of the induction-coil, is mounted a current-selector switch 27, 70 swinging on a binding-post 28 in electrical connection with the electrode-plate 3 through the medium of a contact-spring 29, mounted upon the base in contact with the plate and connected to one end of the wire a, the other 75 end of which is connected to the binding-post 28. At opposite sides of the selector-switch are mounted binding-posts 30 and 31, constituting the opposite terminals of the secondary coil, the terminal wires b and c of 80 which are connected to the posts, as indicated in Fig. 4. The primary circuit is established through the primary wire d, led, as indicated in Fig. 4, from the screw 23^a to the binding-post 20 of the interrupter. One end 85 e of the primary wire leading from the primary coil 14 is led into contact with the plate 16 of the interrupter, as indicated in Figs. 2 and 6, and is then extended, as indicated at f, to the contact-spring 32, mounted upon 90 the base in a manner similar to the plate 29, but contacting with the electrode-plate 4. The primary wire g leading from the opposite end of the primary coil is electrically connected with the binding-post 30, from 95 whence is led a wire h, having electrical connection with the screw 23. The primary circuit may be traced as follows: from the binding-post 24 of the battery, through the arm 21, wire d, thence through the interrupter, 100 wire e, primary coil 14, wire g, to binding-post 30, wire h, and arm 22, to the binding-post 25 of the battery. Supposing now that a direct battery-current is required, the selector-switch 27 is moved into contact with 105 the post 30 and the electrode-plates 3 and 4 are brought into contact with the surface of the body. The circuit will then be established through the plate 3, wire a, switch 27, wire h to battery, thence through wire e, 110 interrupter, wire f, plate 4, and thence diffusing through the portion of the body in contact with the electrodes. If, on the other hand, a faradic current is desired, the switch 27 is moved into contact with the binding-post 31, and the circuit will then be as follows: electrode 3, wire a, switch 27, secondary 115 wire c, thence through the secondary coil 15, wire b, and binding-post 30. The faradic current will thence pass into the primary 120 wire h, through the battery, (assuming that the resistance of the battery is less than the resistance of the primary coil,) thence through the wire d to the interrupter, and through the wire f to the electrode 4 for diffusion. At 125 the same time the primary or exciting circuit will be maintained as has been heretofore traced. It will thus be evident that either a direct battery-current or a faradic current may be utilized, as desired, in the treatment 130 of the patient, and it only remains to state that when a faradic current is utilized its

strength may be regulated accurately and without removing the electrodes from contact with the patient. This regulation is effected by means of the usual core-cover or regulating-sleeve 33, slidably mounted upon the core 13 of the induction-coil and provided with a handle 34, preferably formed from wire and connected to the front end of the sleeve, as indicated in Figs. 2 and 5.

10 The handle is carried to one side of the induction-coil and is then passed rearwardly and provided with a loop or other finger-piece 34, located opposite the induction-coil and designed to be guided by a guide 35, formed 15 by a double strand of wire extending between the head-blocks 11 and 12. It is also contemplated to utilize the device for unipolar and extension bipolar applications with conducting-cords, and the base is therefore provided 20 at the side opposite the selector-switch with binding-posts 36 and 37, electrically connected with the apparatus—as, for instance, by wires *i* and *k*, leading from the binding-posts to the wires *a* and *f*. These binding- 25 posts are designed for the connection of the conducting-cords for the unipolar and extension bipolar applications and render the apparatus capable of doing all that the usual forms of ordinary medical induction-coils 30 can do in addition to those special objects which have been heretofore pointed out.

From the foregoing it will appear that the electrode-plates 3 and 4 are shaped with special reference to their utilization as massage devices and that by their location at the opposite ends of the base the movement of the instrument in the direction of its major axis will bring a large amount of tissue within the electrical field and will subject it alternately 40 to the positive and negative polarity by the successive proximity of the anode and cathode, which is a feature of vast importance in electrotherapeutic massage treatments. It will also appear that the instrument is of 45 small and compact form and capable of being manipulated continuously and without interruption for the purpose of regulating the current or of selecting a faradic or constant battery current, as desired, and that while the 50 instrument may be used for unipolar and extension bipolar applications all electrical connections are ordinarily inclosed and protected between the base and the electrode-plates, with the exception of the circuit breaker or 55 interrupter at one end of the handle and the retaining and conducting arms at the opposite site end thereof.

It is thought that from the foregoing the construction, arrangement, and many advantages of the invention will be clearly understood; but while the present embodiment of the invention is thought at this time to be preferable I do not wish to limit myself to the structural details defined, as, on the contrary, I reserve the right to effect such changes, 65 modifications, and variations as may be fairly

embraced within the scope of the protection prayed.

What I claim is—

1. In a device of the character described, 70 the combination with a base, of electrodes disposed at one side thereof, a handle located at the opposite side of the base, a battery within said handle, and suitable electrical connections between the electrodes and battery. 75

2. In a device of the character described, the combination with a base, of a pair of massaging-plates disposed at one side of the base and constituting electrodes, a battery-cell disposed at the opposite side of the base and 80 constituting a handle for the device, and an electrical circuit including the battery and having its terminals connected with the plates.

3. In a device of the character described, 85 the combination with a base, of electrode-plates located at one side thereof, and a battery located at the opposite side thereof, and constituting a handle for the device, and an induction-coil disposed between the handle 90 and base and in circuit with the battery and electrode-plates, respectively.

4. In a device of the character described, the combination with a base, and electrode-plates disposed opposite its under face, of a 95 battery arranged opposite the upper face of the base and constituting a handle for the device, an induction-coil located between the battery and base, suitable electrical connections between the battery, induction-coil and 100 electrode-plates, and a selector-switch disposed to establish electrical connection with the plates and battery to produce a direct battery-current, or to place said plates in circuit with the induction-coil to induce a faradic current. 105

5. In a device of the character described, the combination with a base, and electrodes disposed opposite one side thereof, of a battery constituting a handle disposed at the 110 opposite side thereof, and electrical connections between the electrodes and battery, said connections including a retaining device for the battery.

6. In a device of the character described, 115 the combination with a base and electrodes disposed at one side thereof, of a battery located at the opposite side thereof and constituting a handle, and electrical connections between the battery and electrodes, said connections including a pair of conductive retaining-arms engaging the binding-posts of the battery to retain the latter in place. 120

7. In a device of the character described, the combination with a base, and electrodes, 125 of a battery detachably associated with the base and constituting a handle therefor, and electrical connections between the battery and electrodes, said connections including a pair of swinging arms mounted on the base and 130 engaging the binding-posts of the battery, whereby said arms constitute electrical con-

ductors, retaining devices for the battery, and means for opening and closing the battery-circuit.

8. In a device of the character described, 5 the combination with a base, and a pair of electrode-plates secured to one side thereof, and insulated from each other, of a battery disposed at the opposite side of the base and constituting a handle for the device, an induction-coil interposed between the handle and the base, and electrical connections between the battery, induction-coil and electrode-plates, said connections including wiring inclosed between the electrode-plates and 15 the base.

9. In a device of the character described, the combination with a base and electrode-plates disposed at one side thereof, of a battery located at the opposite side of the base 20 and constituting a handle for the device, an induction-coil interposed between the battery and the base, suitable connections between the battery, induction-coil, and electrode-plates, a regulator-sleeve slidably 25 mounted on the core of the induction-coil, and a handle for said regulator-sleeve located at one side of the induction-coil.

10. In a device of the character described, the combination with a base, and electrode- 30 plates disposed at one side thereof, of a battery disposed at the opposite side of the base and constituting a handle for the device, an induction-coil disposed between the battery and base, electrical connections between the 35 battery, induction-coil and electrode-plates, said connections including a selector-switch, and conductive arms serving to retain the battery.

11. In a device of the character described, 40 the combination with an elongated base, of a battery disposed longitudinally of the base at one side thereof and constituting a handle for the device, electrode-plates located at the ends of the base at the opposite side thereof, 45 and electrical connections between the bat-

tery and plates, the relative arrangement of the plates with respect to the handle serving to subject the tissues over which the instrument is passed to positive and negative polarity in succession.

12. In a device of the character described, 50 the combination with a base, of concavo-convex massage and electrode plates disposed at one side thereof and insulated from each other, a battery disposed at the opposite side 55 of the base and constituting a handle, and electrical connections between the battery and said plates.

13. In a device of the character described, 60 the combination with a base, of electrode-plates located at one side thereof and a secondary coil disposed at the opposite side of the base and secured thereto, a battery supported upon said coil and constituting a handle for the device, retaining-bands secured 65 to the base and passed around the battery, electrical connections between the battery, induction-coil and electrode-plates, and swinging retaining-arms comprising elements 70 of the electrical connections and arranged to engage the binding-posts of the battery to retain the same in position within the bands.

14. In a device of the character described, 75 the combination with a base, of electrode-plates at one side thereof, a battery removably mounted at the opposite side thereof and constituting a handle for the device, electrical connections between the battery and the plates, and retaining devices opposed to the opposite ends of the battery, one of said 80 retaining devices being movable to release the battery for the purpose of permitting its withdrawal.

In testimony that I claim the foregoing as my own I have hereto affixed my signature in 85 the presence of two witnesses:

LEE J. CHAPMAN.
